UNITED STATES PATENT OFFICE.

WILLIAM S. SHARPNECK, OF CHICAGO, ILLINOIS, ASSIGNOR OF TWO-THIRDS
TO JOHN D. ROSS AND EVERETT W. BROOKS, OF SAME PLACE.

MULTIPLE-PISTON EXPLOSIVE-ENGINE.

SPECIFICATION forming part of Letters Patent No. 680,985, dated August 20, 1901.

Application filed December 13, 1900. Serial No. 39,751. (No model.)

To all whom it may concern:

Be it known that I, WILLIAM S. SHARPNECK, a citizen of the United States, residing at Chicago, in the county of Cook, State of Illinois, 5 have invented a certain new and useful Improvement in Gas-Engines, of which the following is a specification, reference being had to the accompanying drawings.

This invention relates to an improvement 10 in gas-engines of that class in which a plurality of pistons are employed; and one of the objects of the invention is to make an engine of this class in which the pistons will have two full movements in each direction to each 15 single rotation of the crank-shaft.

Another object is to utilize the main shaft as a valve to admit and exhaust the motive fluid.

With these objects in view my invention 20 consists in the peculiar construction, arrangement, and combinations of parts hereinafter described and then definitely claimed at the end hereof.

In the accompanying drawings, which represent an embodiment of my invention in a simple form, Figure 1 represents a side elevation of my improvement. Fig. 2 is a vertical cross-section of the same. Fig. 3 is a section through the main shaft at right angles 25 to that shown in Fig. 2, and Fig. 4 is a detail of the connection between the toggle and connecting-rod.

Referring now to the details of the drawings by numerals, 1 represents the base of 30 the engine, provided, preferably, with integral columns or standards 2 2, on the upper ends of which are formed the bearings 3 for the shaft 4, the latter being provided with the fly or balance wheels 5, on each of which is 35 formed a wrist-pin 5^a. Between the columns or standards 2 2 is preferably integrally formed the cylinder 6, which may be made of any approved type and be provided with the usual water-jackets 7 and 8; but in the form 40 shown in my drawings it is provided with open ends and with sides bifurcated or slotted at 9 9. Within this cylinder are two pistons 10 10, one at each end, and these pistons are provided with trunnions or gudgeons 11 11, 45 on which are journaled at each side of the engine connecting-rods 12 12, the inner ends

of which are pivoted together at 13, forming a toggle. Between the joints of these toggles and the wrist-pins 5^a are the connecting-rods 14, one on each side of the engine, and these 55 form the means of transforming the reciprocating movement of the pistons and toggles to the rotary movement of the main shaft.

The pivots 13, which connect the pivoted ends 15 and 15^a of the toggle-arms 12 and the 60 straddling yoke 14^a of the connecting-rod 14, are extended inwardly and provided with a dovetailed slide-block 16, (see Fig. 4,) one for each pivot 13, which blocks 16 travel up and down in guides 17, formed in the columns or standards 2, (see Fig. 1,) and by this means the same amount of motion or length of stroke is insured to each piston. It is evident that instead or a dovetailed slide-block 65 a roller may be used, if desired.

Between the pistons 10 10 within the cylinder 6 is formed an exploding and compressing chamber 18, communicating with which is a port 19, common to both the exhaust and inlet. This port 19 is best shown in Fig. 2, 70 and at its upper end communicates with an inlet-port 20 and an exhaust-port 21, the main shaft 4 being cut away at 20^a and 21^a, so as to alternately afford communication between said inlet and exhaust ports and the common 75 port 19. It will be observed that the ports 20^a and 21^a in the main shaft are "quartering" or at right angles with each other, or, in other words, they each communicate in turn with the common port 19 during the same 80 half-revolution, and during the other half-revolution of the main shaft neither port is open, as during this time the charge is being compressed and exploded, as will now be described in detail.

From a study of my drawings it is obvious that each of the pistons makes two complete strokes in each direction while they are rotating the main shaft only once. This being recognized, the operation is as follows: Supposing the wrist-pins to be at their lowest positions, the pistons consequently drawn toward each other, and the charge compressed, the explosion occurs just as the wrist-pins pass the dead-center, and the pistons are thereby driven outwardly when the wrist-pins will reach the point marked a. 90 95 100

Then as the pistons approach each other, the 5 wrist-pins turning around to *b*, the burned charge is pumped out. During the next or outward stroke of the pistons, when the 10 wrist-pins turn to *c*, the new charge is drawn in, and on the last quarter of movement, when the wrist-pins again reach their lowest 15 positions, the pistons draw toward each other and compress the charge for the next explosion, which occurs, as before, just as the 20 said wrist-pins pass their dead-centers and the toggle-joint begins to move upwardly again. As hereinbefore stated, it will thus be seen that the pistons move outwardly, 25 then inwardly toward each other, outwardly again, and finally toward each other again all during one rotation of the crank-shaft and that during this one rotation the charge 30 is exploded, the burned charge pumped out, a new charge drawn in, and then compressed ready for the next explosion.

It is obvious that many changes may be 35 made and still retain the essence of my invention, and of course I do not, therefore, limit my invention to the exact construction shown, 40 but intend my claims to cover all such fair modifications as naturally fall within the limits of my invention.

What I claim as new is—

30 1. In an engine, a cylinder, a plurality of pistons therein, a shaft, intermediate connections between said shaft and pistons; the parts being so arranged that the pistons have two movements in each direction for each revolution of said crank-shaft, substantially as described.

35 2. In an engine, a cylinder, a plurality of pistons therein, a shaft, and a toggle interposed between said pistons and shaft, substantially as described.

40 3. In an engine, a cylinder, a plurality of pistons therein, a shaft, a toggle connecting said pistons, and a connection between said toggle and shaft, substantially as described.

45 4. In an engine, a cylinder, a plurality of pistons therein, a shaft, a toggle connecting

50 said pistons, a connection between said toggle and shaft, and means for guiding the movement of the toggle and insuring equal movement of the pistons, substantially as described.

55 5. In an engine, a cylinder, a plurality of pistons working therein and having a toggle connecting them, a shaft, a rod connecting said shaft and the central pivot of the toggle, and a guide for the said central pivot, substantially as described.

60 6. In an engine, a cylinder, a plurality of pistons working therein, a toggle comprising two parts pivotally connected with said pistons, a shaft, a rod connecting said shaft and said toggle, the central pivot of the toggle projecting therefrom, and columns or standards provided with guides for said central pivot, substantially as described.

65 7. In an engine, a suitably-supported cylinder, a plurality of pistons working therein, a toggle connecting said pistons, a shaft and rod connecting it with said toggle, the central pivot of the toggle projecting therefrom and 70 having a slide-block secured thereto; and a column or standard having a guide for said slide-block, substantially as described.

75 8. In an engine, a suitably-supported cylinder having slots therein, a plurality of pistons working in said cylinder and having pivots projecting through said slots, a toggle comprising two arms connected with said pivots and a central pivot connecting said two arms, a shaft and a rod connecting said shaft with 80 said central pivot, columns or standards supporting said crank-shaft, and guides in said columns for the central pivot of said toggle, substantially as described.

85 In testimony whereof I affix my signature, in the presence of two witnesses, this 10th day of December, 1900.

WILLIAM S. SHARPNECK.
